EVERETT S. WOOD AND JONAS NORTHROP, OF HOPEDEALE, MASSACHUSETTS, ASSIGNEES TO DRAPER COMPANY, OF HOPEDEALE, MASSACHUSETTS, A CORPORATION OF MAINE.

FILLING-EXHAUSTION INDICATING AND CONTROLLING MECHANISM FOR LOOMS.

SPECIFICATION forming part of Letters Patent No. 789,472, dated May 9, 1905.

Application filed February 18, 1905. Serial No. 246,231.

To all whom it may concern:

Be it known that we, EVERETT S. WOOD and JONAS NORTHROP, citizens of the United States, and residents of Hopedale, county of 5 Worcester, State of Massachusetts, have invented an Improvement in Filling-Exhaustion Indicating and Controlling Mechanism for Looms, of which the following description, in connection with the accompanying 10 drawings, is a specification, like characters on the drawings representing like parts.

This invention has for its object the production of novel and accurately-operating mechanism to positively control and effect a 15 change in the operation of a loom when the filling in the running shuttle has become substantially exhausted or woven off to a predetermined extent. The change in the operation of the loom may be the automatic stop- 20 page thereof to enable the weaver to provide the running shuttle with a fresh supply of filling, or it may be the actuation of mechanism to automatically effect replenishment of the running filling without stopping the loom. 25 Replenishment of the running filling automatically may be effected by mechanism of the "Northrop" type, shown in United States Patent No. 529,940 and others, wherein a fresh supply of filling is inserted automatically in a 30 running shuttle of the automatically self-threading class without stopping or varying the speed of the loom. As such looms are in extensive use, we have herein illustrated one practical embodiment of our invention in connection with a loom provided with automatic filling-replenishing mechanism of the Northrop type hereinbefore referred to.

The filling-exhaustion-indicating mechanism in the present embodiment of our invention 40 comprehends two movable members, one of which intermittently impinges on and is moved by means within the shuttle until the running filling is exhausted to a predetermined extent, and an actuator operatively 45 connected with such member mounted on and movable relatively to the other member into inoperative position by the intermittent movement of the first-named member. The mem-

ber on which the actuator is mounted is movable by impingement on a vibrating part of 50 the loom only when the predetermined exhaustion of the filling permits, thereby causing the then relatively quiescent and operatively-positioned actuator to effect the actuation of mechanism which controls the operation of the loom. Inasmuch as one of the members supports or carries the other member, we have hereinafter designated the former as the "carrier," and the member supported thereby is termed the "feeler," as it intermittently impinges upon and feels the filling in the running shuttle to indicate the volume thereof or, in other words, its degree of exhaustion. Up to the point of predetermined exhaustion of the filling the feeler acts on 60 each feeling movement thereof to move the actuator relatively to the carrier on which it is mounted and renders the actuator inoperative. When predetermined filling exhaustion is reached, however, the feeler becomes 65 dead or inert with respect to both filling and actuator, and hence is ineffective to render the actuator inoperative, and the same remains quiescent with relation to the carrier. At such time the carrier is impinged on and 70 moved by a vibrating part of the loom, such as the shuttle, and the relatively quiescent actuator is moved with the carrier as a unit to effect the actuation of the controlling mechanism for the loom. The construction is simple, direct, and positive in its action and so arranged that the change in the operation of the loom is impossible until the filling in the running shuttle is exhausted to the predetermined extent. Herein there is no pressure 75 whatever on the filling carrier or bobbin at the instant of filling replenishment, for such operation is effected when the shuttle engages the carrier or a part fixedly mounted thereon, the feeler at such time being dead or inert 80 and performing no work.

The various novel features of our invention will be fully described in the subjoined specification, and particularly pointed out in the following claims.

Figure 1 is a top or plan view of a portion

of the left-hand side of a loom with one embodiment of our invention applied thereto, the running shuttle being in position for co-operation with the filling-exhaustion-indicating mechanism on the forward beat of the lay. Fig. 2 is a left-hand side elevation of the mechanism shown in Fig. 1 with a portion of automatic filling-replenishing mechanism shown at the opposite side of the loom. 5 Fig. 3 is a rear elevation of the transmitter intermediate the feeling devices and the replenishing mechanism to be described. Fig. 4 is an inner side elevation, enlarged, taken at the left of the line 4-4, Fig. 1, of the feeling devices and a portion of the transmitter. Fig. 5 is a much-enlarged longitudinal section on the line 5-5, Fig. 1, taken through the center of the carrier, the parts being in normal position. Fig. 6 is a transverse section 10 on the line 6-6, Fig. 5; and Fig. 7 is a top or plan view of the carrier and feeler, a portion of the actuator being broken off to show the part beneath it.

The filling-feeder F, Fig. 2, mounted on the breast-beam A⁴⁰ and adapted to contain a supply of filling carriers or bobbins b, the trans-ferrer f' to transfer them one by one to the automatically self-threading shuttle S, and the controlling rock-shaft d' to effect the replenishment of filling may be and are all substantially as in the Northrop patent referred to, an upturned arm d², fast on the rock-shaft, having pivotally connected with it a rearwardly-extended latch d³ to at times co-operate with a vibrating actuator, shown as the weft-hammer W. When the rear end of the latch is moved into the path of the head W', it enters a recess w^x therein, (see dotted lines, Fig. 2,) and the forward movement of the weft-hammer pushes the latch forward, acting through arm d² to turn the rock-shaft d' in the direction of arrow 200, Fig. 2, to effect the operation of the replenishing mechanism in well-known manner. The actuator, latch, rock-shaft, and intervening connections constitute controlling means for the loom and herein operate to govern the time of operation of the replenishing mechanism. 35

Novel filling-exhaustion-indicating mechanism effects the actuation of the controlling means when and only when the filling in the shuttle has become exhausted to a predetermined extent, so that it is impossible to eject a bobbin from the shuttle until the filling has 50 been woven off to the desired extent, thus greatly reducing waste, and, on the other hand, when the predetermined exhaustion is attained a fresh supply of filling is with certainty provided, so that there will be no pick devoid or partly devoid of filling. 55

The shuttle S has an opening 1 in its side wall (see dotted lines, Fig. 1,) to register with the usual opening 1^x (see Fig. 1) in the front wall 2 of the shuttle-box 3 when the 60 shuttle is properly boxed therein. 65

The notched holding-plate 4 for the shipper S^x is depressed at its outer end at 5 to support a vertically-adjustable bracket 6, having an inclined top 7, on which is adjustably secured by screws 8 a stand 9. By inclining the 70 bracket-top 7 the stand is so inclined that the feeler, to be referred to, moves in a path closely coincident with the path of the lay A³ as it swings back and forth, so that filling in the shuttle impinging on the feeler acts substantially directly along its path of movement, obviating any bending or twisting tendency and imparting greater accuracy to the operation of the apparatus. In Fig. 2 the shipper is omitted for the sake of clearness of illustration. The stand is conveniently made in two parts bolted together and chambered out at 10, Fig. 5, to receive a transverse and rectangular enlargement 11 on the carrier, which forms one member of the filling-exhaustion-indicating mechanism. The carrier (see Figs. 5 and 7) is preferably made as a flat elongated plate 12 of metal, having at its rear end a lateral enlargement or head 13 and at its forward end the enlargement 11, beyond which there 90 is a preferably cylindrical shank 14, freely 95 slideable through an opening in the front end of the stand 9. The enlargement 11 slides freely in the chamber 10 and is guided by the sides and top thereof, and a spring 15, coiled 100 around the shank 14 between said enlargement and the front end of the stand, serves to move the carrier rearward into the position shown in Fig. 5, the rear end of the stand limiting such movement. Said end 16 has an opening 17, Fig. 6, to receive the body portion 12 of the carrier and slidably support it. Upturned parallel ears 18 on the rear end of the carrier adjacent its head are connected by a cross-piece 19, having a threaded hole 20 to receive 105 the threaded shank of a bunter 21, adjustable in the cross-piece and held in adjusted position by a check-nut 22. The flat body 12 is centrally and longitudinally slotted at 23 from the head 13 to the enlargement 11, and adjacent 110 the latter short parallel guideways or flanges 24 are formed on the sides of the slot. We have herein shown an actuator movably mounted on the carrier, said actuator being 115 made as an elongated arm 26, fulcrumed between the ears 18 on a horizontal pin 27, and having a short lug 25 depending below the fulcrum, the actuator 26 being extended forward above the carrier and prolonged to project above the top of the stand 9, as clearly 120 shown in Fig. 5.

The third member of the filling-exhaustion-indicating mechanism is the feeler, and herein it comprises a broadened head 28 and an elongated shank 29, the feeler being made of metal 125 and light in weight, its head being recessed transversely on its under side at 30 to receive the head 13 of the carrier. The feeler-shank freely enters the slot 23 and at its forward end rests upon the guideways 24 within the 130

opening 16, the shank passing under the cross-bar 19 and between the ears 18, as shown. A very slight longitudinal sliding movement of the feeler upon the carrier is provided by 5 making the fore-and-aft width of the recess 30 greater than the distance from front to rear of the carrier-head 13, as clearly shown in Fig. 5. We have provided a positive connection between the feeler and the actuator 26 by introducing 10 the lower end of the lug 25 between transverse shoulders 31 on the feeler-shank, (see Fig. 5,) and owing to the great difference in lever-arms, comparing the lug 25 and actuator 26, the slight forward movement of the feeler 15 on the carrier is sufficient to elevate the tip of the actuator a considerable distance above the top of the stand 9. Consequently when the lay beats up and the shuttle is boxed in the shuttle-box 3 the feeler will enter the shuttle 20 and impinge upon the filling, and the feeler will thereby be moved forward relatively to the carrier. The slight distance permitted by the clearance of the head 13 in the recess 30 before the continued forward movement of 25 the lay will move feeler and carrier in unison against the action of the spring 15. This initial filling induced and relative movement of the feeler acts through the lug 25 to in-operatively position the actuator 26 by swinging 30 it upward in the construction herein illustrated, so that when the carrier begins to move forward with the feeler the actuator will be inoperative and will remain so during the forward stroke of feeler and carrier. On the 35 return stroke, the lay swinging back, the spring 15 serves to return the carrier to the position shown in Fig. 5, and after the filling recedes from the feeler the weight of the actuator 26 returns it to normal position and 40 through lug 25 sets the feeler in impinging position in readiness for the next feeling stroke. Until such time as the filling in the shuttle is exhausted to a predetermined extent the feeler and carrier will be moved outward intermittently, first inoperatively positioning the actuator on each active stroke, the 45 amplitude of filling-induced movement of the feeler and carrier gradually decreasing as the diameter of the yarn mass on the filling carrier or bobbin diminishes. As such amplitude of movement decreases the distance between the bunter 21 and a vibrating part of the loom, such as the front side wall of the shuttle, also gradually decreases, so that when 50 the desired or predetermined filling exhaustion is reached the bunter will impinge upon the shuttle. At that instant the diminution in the diameter of the yarn mass permits the feeler-head to extend so far into the shuttle 55 that there can be no filling-induced movement of the feeler, the latter thus lying dead or inert on the carrier, and consequently the actuator will remain quiescent with relation to the carrier and in its operative position. 60

65 Then the continued forward movement of the

lay as it completes its stroke will move the carrier and actuator forward together as a unit, the inert feeler maintaining the position relative to the carrier shown in Figs. 5 and 7. The means for causing the forward movement of the operatively-positioned actuator to effect a change in the operation of the loom 70 will now be described. It is to be observed, however, that while there is sufficient filling in the shuttle to impart movement to the feeler by impingement thereon such movement will cause the actuator to be inoperatively positioned, so that no change in the operation of the loom can be effected until just the desired point of exhaustion of filling is reached. By 75 means of the adjustment of the bunter 21 the quantity of filling remaining at such time is regulated to a nicety, and the indicating mechanism is also thereby adjusted for bobbin diameter and width of shuttle. 80

The plate 4 is provided with an upturned ear 32, which carries a fulcrum-stud 33, Figs. 1 and 3, substantially parallel to the path of movement of the reciprocating carrier 12 14, and on said stud is fulcrumed a transmitter 90 (shown as a lever 34 35) operatively connecting the latch d^3 and the filling-feeling device. The free end of the arm 34 extends beneath the latch and normally sustains it in inoperative position, a lug 36 on said arm then resting on the top of the breast-beam. (See Fig. 3.) At the opposite or outer end of the transmitter the arm 35 is bent laterally and forms an upright ear 37 (clearly shown in Fig. 4) adjacent a guide 38 on the stand 9, the ear 100 having a cam-slot 39 therein. A controller for the transmitter is provided in positive and sliding connection therewith and so constructed that the movement of the transmitter from inoperative to operative position, or vice 105 versa, is effected positively, the controller locking said transmitter in either position. The controller is shown best in Fig. 1 as an arm 40, fulcrumed on an upright stud 41, carried by a bracket 42, secured to the ear 32, the studs 33 and 41 being substantially at right angles to each other. The free end of the controller passes through the cam-slot 39 and under the guide 38 across the top of the stand 9, the controller end or foot 43 extending into the operative path of movement of the actuator 26, the rear edge of the foot being shown as notched, as at 44, (see dotted lines, Fig. 5,) while the free end or tip of the actuator is beveled on both sides or brought to an edge, at 45. If the parts are in the position shown in Fig. 4, the controller being then in the low portion of the cam-slot 39, it will be manifest that movement of the controller to the left or toward the front of the 110 loom will act through the cam-slot to depress the adjacent end of the transmitter and rock the latter on its fulcrum 33. The arm 34 is thereby elevated, and the latch d^3 is moved into 115 position to be engaged by its actuator—viz., 120

125

130

the weft-hammer W—as hereinbefore referred to. Inasmuch as the peculiar connection between the controller and transmitter locks the latter in position, it will be manifest 5 that the transmitter will be unaffected by shock or jar and can only be operated or rocked through movement of the controller. Remembering that so long as there is sufficient filling in the shuttle the impingement of 10 the feeler upon the filling will move the actuator into inoperative position with its sharpened tip 45 above the foot 43 of the controller, it will be clear that no movement of the latter can then be effected, and when the tip 45 15 passes beyond the notched edge of the foot it is impossible for the actuator to coöperate with and move the controller. When, however, the exhaustion of filling reaches the desired point, there will be no filling-induced 20 movement of the feeler, and the actuator will remain operatively positioned, as shown in Fig. 5, when the bunter 21 impinges on the shuttle, and as the feeler-carrier is moved forward by the lay as it completes its forward beat 25 the tip of the actuator engages the notched edge 44 of the controller and moves the latter forward as the stroke of the feeler-carrier is completed. The transmitter is thereby rocked on its fulcrum, and the operation of the controlling means for the loom will be effected. 30 Should the controller jump forward away from the actuator or the bunter away from the shuttle after engagement therewith, as may sometimes happen, it would not be material, for 35 the feeler is then inert and there is nothing to move the actuator relatively to the feeler-carrier, and the engagement of actuator and controller will be effected when the former catches up with the latter. Ordinarily, however, 40 the engagement of the sharp end or tip of the actuator with the notch 44 in the edge of the controller will be maintained when once effected until the actuator and controller have effected the operation of the transmitter. 45 If the tip of the actuator passes above the top of the controller, no matter how slight the clearance, there will be no actuation of the controller, while, on the other hand, if the tip is ever so little below the sharp edge formed 50 by the top of the foot 43 and the beveled upper side of the notch 44 then the controller will be actuated. A very certain operation is thus insured when called for and premature operation is completely eliminated. 55 A spring 46 is coiled around the stud 41 and fixed at one end, its other end being connected with the controller 40, the spring being so wound that it acts normally to hold the controller in the low or rear end of the cam-slot 60 39, with the transmitter locked in inoperative position.

The filling-exhaustion-indicating mechanism is manifestly adapted to control either a filling-replenishing mechanism or a loom-stopping mechanism, either mechanism con-

stituting means to control the operation of the loom, the filling-exhaustion-indicating mechanism governing the operation of such controlling means.

Various changes or modifications in construction and arrangement may be made by those skilled in the art without departing from the spirit and scope of our invention, herein shown and described in one practical and efficient form. 70

Having fully described our invention, what we claim as new, and desire to secure by Letters Patent, is—

1. In a loom, a shuttle to contain a supply of filling, filling-replenishing mechanism, and means to control the time of its operation, combined with an actuator, a movable carrier on which it is mounted, a feeler independently mounted on the carrier, filling-induced movement of the feeler effecting movement of the carrier, and means governed by such feeler movement to prevent coöperation of the actuator and said controlling means until exhaustion of the filling to a predetermined extent. 80 85

2. In a loom, a shuttle to contain a supply of filling, filling-replenishing mechanism, and means to control the time of its operation, combined with a reciprocating carrier, and a feeler and an actuator, independently mounted thereon, filling-induced movement of the feeler preventing coöperation of the actuator and said controlling means until predetermined exhaustion of the filling in the shuttle. 90 95

3. In a loom, a shuttle to contain a supply of filling, filling-replenishing mechanism, means to control the time of its operation, including a reciprocating carrier, a feeler mounted thereon to intermittently engage and be moved by the filling in the shuttle until predetermined exhaustion thereof, filling-induced movement of the feeler effecting movement of the carrier, and means, operative upon failure of the filling to impinge upon the feeler, to effect the operation of the filling-replenishing mechanism independently of the feeler. 100 105 110

4. In a loom, a swinging lay, a shuttle movable thereon and adapted to contain a supply of filling, filling-replenishing mechanism, and means to control the time of its operation, including a reciprocating carrier, a relatively movable feeler thereon adapted to intermittently impinge upon and be moved by means within the shuttle until substantial exhaustion of the filling, such feeler movement also causing movement of the carrier, and a bunter fixedly mounted on the carrier, impact of a vibrating part upon the bunter acting independently of the feeler to move the carrier and effect the operation of the replenishing mechanism. 115 120 125

5. In a loom, a swinging lay, a shuttle movable thereon and adapted to contain a supply of filling, filling-replenishing mechanism, and means to control the time of its operation, including a reciprocating carrier, a relatively 130

movable feeler thereon adapted to intermittently impinge upon and be moved by means within the shuttle until substantial exhaustion of the filling, such feeler movement also causing movement of the carrier, a bunter, and adjustable means to fixedly connect it with the carrier, impact of a vibrating part upon the bunter acting therethrough independently of the feeler to move the carrier and effect filling replenishment.

6. In a loom, a swinging lay, a shuttle movable thereon and adapted to contain a supply of filling, filling-replenishing mechanism, and means to control the time of its operation, including a yieldingly-sustained reciprocating carrier, a relatively movable feeler thereon adapted to intermittently engage and be moved by the filling in the shuttle until substantial exhaustion thereof, such feeler movement also moving the carrier, a fixedly-mounted bunter on the carrier, and a relatively movable actuator thereon, filling-induced movement of the feeler rendering the actuator inoperative and also preventing impact of the bunter on the shuttle, such impact acting to move the carrier and actuator in unison upon failure of the filling to impinge upon the feeler, to thereby cause the operation of the replenishing mechanism.

7. A controlling mechanism for looms, having two members adapted to be impinged upon, an actuator mounted on one member and operatively connected with the other member and movable relatively thereto, means for impinging on one member to thereby position inoperatively said actuator, and means, when exhaustion of the filling permits, for impinging on the other member, to move the actuator while operatively positioned and thereby cause the actuation of the controlling mechanism.

8. A controlling mechanism for looms, having two members adapted to be impinged upon, one supporting the other, an actuator mounted on one member and movable relatively to both members, means for impinging on one member to thereby position inoperatively said actuator, and means, when exhaustion of the filling permits, for impinging on the other member, to move the actuator while operatively positioned and thereby cause the actuation of the controlling mechanism.

9. A controlling mechanism for looms, having two members adapted to be impinged upon, one supporting the other, an actuator mounted on one member and movable relatively to both members, means for impinging on one member to move it longitudinally and thereby position inoperatively said actuator, means, when exhaustion of the filling permits, for impinging on the other member, to move the actuator while operatively positioned and thereby cause the actuation of the controlling mechanism, and means to restore said members to impinging position.

10. In a loom, controlling means therefor, and a shuttle to contain a supply of filling, combined with filling-exhaustion-indicating mechanism comprising two longitudinally-movable members, one of which is supported by the other, and an actuating device pivotally mounted on one member and loosely connected with the other member, impingement of one member on means within the shuttle rocking said device relatively to the other member into inoperative position, exhaustion of the filling in the shuttle to a predetermined extent permitting said latter member to impinge upon the shuttle, to move bodily the actuating device while operatively positioned and thereby effect the operation of the controlling means.

11. In a loom, in combination, a running shuttle, and mechanism to automatically provide the same with a supply of filling, combined with a feeler adapted to intermittently impinge upon and be moved by the filling in the shuttle until predetermined exhaustion thereof, a carrier for the feeler, adapted, when exhaustion of the filling permits, to impinge upon the shuttle and be moved thereby, an actuator movably mounted on the carrier and operated by shuttle-induced movement of the carrier, to effect the operation of the filling-supplying mechanism, and a pivotal connection between the actuator and feeler, filling-induced movement of the latter rendering the actuator inoperative and preventing the operation of the filling-supplying mechanism.

12. In filling-exhaustion-indicating mechanism for looms, in combination, a feeler device having two members adapted to be impinged upon, an actuator mounted on one, and controlled by the other of said members, means for impinging on one of said members and thereby rendering inoperative said actuator, means, when exhaustion of the filling permits, for impinging on the other member to move the actuator while operatively positioned, a transmitter, and a controller to lock and also move the same, movement of the operatively-positioned actuator acting through said controller to unlock and move the transmitter.

13. In filling-exhaustion-indicating mechanism for looms, in combination, a feeler device having two longitudinally-movable members adapted to be impinged upon, one member supporting the other, a spring to control movement of the supporting member, an actuator pivotally mounted on the latter member and loosely connected with the supported member, means for impinging on the supported member and moving it to render inoperative the actuator and thereafter to move the supporting member against its spring, means, when exhaustion of the filling permits, for impinging on the supporting member, to move it and the actuator while operatively positioned, and a transmitter operated by or through such movement of the actuator.

14. In a loom, filling-exhaustion-indicating mechanism, consisting of a spring-controlled, reciprocating carrier, means for moving it through impact of the shuttle when the lay 5 beats up, an actuator movably mounted on the carrier, and a feeler operatively connected with said actuator, slidably mounted on the carrier and adapted when impinged upon to render the actuator inoperative and also to 10 move the carrier against its spring, and an instrumentality operated by or through coöperation with the actuator when the latter is moved by impact of the shuttle on the carrier.

15. In a loom, filling-exhaustion-indicating 15 mechanism, consisting of a spring-controlled, reciprocating carrier, a fixed bunter and a rocking actuator thereon, a feeler operatively connected with the actuator and slidably mounted on the carrier, means for impinging 20 on the feeler and thereby rocking and inoperatively positioning the actuator, means, when exhaustion of the filling permits, for impinging on the bunter and thereby moving the carrier and actuator in unison while the 25 latter is operatively positioned, and an instrumentality operated by or through such movement of the operatively-positioned actuator.

16. In filling-exhaustion-indicating mechanism for looms, in combination, a feeler adapted 30 to intermittently impinge upon and be moved by means within the shuttle, a reciprocating member on which the feeler is mounted and adapted to be moved primarily when the feeler passes a predetermined distance into the shuttle, an actuator pivotally mounted on the said member, connected with and movable relatively to the feeler, movement of the feeler by means within the shuttle rocking the actuator into inoperative position, primary movement 40 of the reciprocating member effecting bodily movement of the actuator while operatively positioned, and a transmitter operatively moved by such bodily movement of the actuator.

45 17. In filling-exhaustion-indicating mechanism for looms, in combination, a feeler adapted to intermittently impinge upon and be moved by filling in the shuttle, a reciprocating carrier on which the feeler is mounted and adapted 50 to be moved primarily when the filling is exhausted to a predetermined extent, an actuator movably mounted on the carrier and operatively connected with the feeler, a transmitter, and a coöperating, positively-connected controller therefor lying in the operative path 55 of movement of the actuator, filling-induced movement of the feeler moving the actuator into inoperative position and also moving the carrier, primary movement of the latter causing 60 the actuator to move in its operative path to engage the controller and effect therethrough the operation of the transmitter.

18. In filling-exhaustion-indicating mechanism for looms, in combination, a reciprocating 65 carrier, a relatively movable actuator

thereon, controlling mechanism operated by the actuator when quiescent on the carrier, a feeler having a limited sliding movement on the carrier, and operatively connected with the actuator, to intermittently engage and 70 be moved by the filling in the shuttle until predetermined exhaustion thereof, filling-induced feeler movement on the carrier moving the actuator relatively to the carrier and preventing its operation, and a bunter fixedly 75 mounted on the carrier and adapted when impinged upon by the shuttle to move the carrier and actuator as a unit and through the actuator cause the operation of the controlling 80 mechanism.

19. In filling-exhaustion-indicating mechanism for looms, in combination, a reciprocating carrier, an actuator pivoted thereon, and having a depending lug, mechanism operated by the actuator, including a controller lying 85 in the path of the actuator when quiescent on the carrier, a feeler having a limited sliding movement on the carrier below the actuator and in engagement with the lug thereof, movement of the feeler by impingement on 90 the filling in the shuttle first lifting the actuator and then moving it across the controller, the carrier moving with the feeler, and a bunter on the carrier, adapted when impinged upon by the shuttle—at the time the filling is 95 predeterminedly exhausted—to move the carrier and actuator as a unit and effect engagement of the actuator and said controller to operate the latter.

20. In filling-exhaustion-indicating mechanism for looms, in combination, a reciprocating carrier, an elongated, forwardly-extended actuator fulcrumed thereon and having a short depending lug, mechanism operated by the actuator and including a controller in the 105 path of the actuator when quiescent on the carrier, a feeler on and having a limited movement relatively to the carrier and operatively connected with the lug of the actuator, filling-induced movement of the feeler first 110 acting to lift the actuator above the controller, preventing its coöperation therewith, and thereafter to move the carrier forward, a bunter on the carrier adapted to be impinged on by the shuttle upon failure of filling-induced 115 feeler movement, such impingement moving the carrier and relatively quiescent actuator forward as a unit to effect coöperation of the actuator and controller, and a spring to effect return movement of the carrier, the 120 weight of the actuator at such time restoring it to operative position and setting the feeler on the carrier.

21. In filling-exhaustion-indicating mechanism for looms, in combination, a reciprocating carrier, an elongated, forwardly-extended actuator fulcrumed thereon and having a short 125 depending lug, a transmitter, a controller positively connected therewith to lock and also effect the operation of the transmitter, said 130

controller having a foot in the path of the actuator, when quiescent on the carrier, a feeler on and having a limited movement relatively to the carrier, and operatively connected with the depending lug, filling-induced movement of the feeler acting first to lift the actuator above the foot and thereafter to move the carrier forward, a bunter on the carrier adapted to be impinged on by the shuttle when the filling therein is exhausted to a predetermined extent to move forward the carrier and cause the relatively quiescent actuator to engage and move the controller a spring to effect return movement of the carrier, and means operative automatically upon such return to insure the operative positioning of the actuator and to set the feeler on the carrier.

22. A controlling mechanism for looms, having two members adapted to be impinged upon, an actuator mounted on one member and operatively connected with and movable relatively to the other member, means for impinging on one member to thereby position inoperatively the actuator, and means, when exhaustion of the filling in the shuttle permits, for impinging on the other member, to move the actuator while operatively positioned and thereby cause the actuation of the controlling mechanism, the member controlling the actuator at such time being inert with respect to the means for impinging thereon.

23. In a loom, means to control its operation, and a shuttle to contain a supply of filling, combined with a feeler adapted to intermittently impinge upon and be moved by the filling in the shuttle until predetermined exhaustion thereof, a carrier for the feeler, adapted, when exhaustion of the filling per-

mits, to impinge upon and be moved by the shuttle, and an actuator movably mounted on the carrier and operatively connected with and movable relatively to the feeler, filling-induced movement of the latter rendering the actuator inoperative, shuttle-induced movement of the carrier moving the operatively-positioned actuator to effect the actuation of the loom-controlling means, the feeler at such times being inert with respect to the filling and the actuator.

24. In a loom, means to control its operation, and a shuttle to contain a supply of filling, combined with a feeler adapted to intermittently impinge upon and be moved by the filling in the shuttle until predetermined exhaustion thereof, a carrier for and upon which the feeler has a limited sliding movement, said carrier being impinged upon and moved by the shuttle when predetermined exhaustion of the filling permits, and an actuator movably mounted on the carrier and normally governed by the feeler, filling-induced movement of the latter rendering the actuator inoperative, shuttle-induced movement of the carrier moving the actuator to effect the actuation of the loom-controlling means, the feeler at such time being inert with respect to the filling and ineffective with relation to the actuator.

In testimony whereof we have signed our names to this specification in the presence of two subscribing witnesses.

EVERETT S. WOOD.
